Primary Examiner — Freda S Nunn(74) *Attorney, Agent, or Firm* — International IP Law Group, PLLC(57) **CLAIM**

The ornamental design for a top loading fan cartridge, as shown and described.

DESCRIPTION

FIG. 1 is a top perspective view of a top loading fan cartridge; FIG. 2 is a front view of the top loading fan cartridge; FIG. 3 is a back view of the top loading fan cartridge; FIG. 4 is a side view of the top loading fan cartridge; and, FIG. 5 is a top perspective view of the top loading fan cartridge being loaded into a top loading server, wherein handles of the top loading fan cartridge are extended.

The broken lines shown in the drawings illustrate portions of the top loading server and form no part of the claimed design.

1 Claim, 5 Drawing Sheets(56)
